UNITED STATES PATENT OFFICE.

BENJAMIN F. D. MILLER, OF WOOSTER, OHIO.

COMBINED IRONING-BOARD AND STEP-LADDER.

No. 804,966.

Specification of Letters Patent.

Patented Nov. 21, 1905.

Application filed July 23, 1904. Serial No. 217,789.

To all whom it may concern:

Be it known that I, BENJAMIN F. D. MILLER, a citizen of the United States, residing at Wooster, in the county of Wayne and State of Ohio, 5 have invented certain new and useful Improvements in a Combined Ironing-Board and Step-Ladder, of which the following is a specification.

My invention relates to an improvement in 10 a combined ironing - board and step - ladder; and the object of the invention is to provide an improved combination step-ladder and ironing-board which is simple in construction and operation and comparatively inexpensive and 15 which may be conveniently used either as an ironing - board or step - ladder whenever desired and which may be compactly folded together when not in use.

With these ends in view the invention consists in the novel construction, arrangement, and combination of parts hereinafter described, illustrated in the accompanying drawings, and particularly pointed out in the appended claims.

25 Referring now to the drawings, forming a part of this specification, Figure 1 is a perspective view of my invention, showing the parts in their proper position when being used as a step-ladder. Fig. 2 is a view of the same 30 when used as an ironing-board. Fig. 3 is a detailed view of a modification of the sliding hinge-bar fastening. Fig. 4 is a longitudinal sectional view of my invention, showing the position of the parts when used as an ironing-board. Fig. 5 is a side view of the same 35 when folded. Fig. 6 is a transverse sectional view of the ironing-board proper, showing a detailed view of the sliding hinge-bar fastening beneath. Fig. 7 is a detailed view of one 40 of the clamps secured to the brace-legs of the ironing-board and step-ladder. Fig. 8 is a detail view showing a portion of one of the brace-legs in section with the bent ends of the hinge-bars extending through the brace-leg.

45 Similar characters of reference indicate like parts throughout all the figures of the drawings.

Referring now to the drawings, 1 designates the ironing-board proper, to one end of which 50 there is hingedly secured the step - ladder proper, comprising two side bars 2, connected by the usual steps 3 and the top board 4.

Near the end of the ironing-board 1, above referred to, there is pivotally secured an aux-

iliary board 5, secured at each side of the 55 board 1 by means of the slotted arms 6, secured at each side of said auxiliary board 5 and adapted to be shifted and turned to any desired position on the pivot-pins 7. The abutting ends of the board 1 and auxiliary 60 board 5 are beveled so as to engage each other when in alinement, as shown in Figs. 2 and 4 of the drawings, so that the board 5 cannot be moved or forced below the position there shown. 65

8 designates brace-legs secured to each other by means of a pair of substantially U-shaped hinge-bars 9 and 9^a, one of which, 9, is pivotally secured to one of the steps 3 of the step-ladder proper, and the other, 9^a, of which is 70 pivotally secured beneath the ironing-board 1 by means of a sliding hinge-bar fastening 10, provided with a sleeve 11, slidably mounted upon a longitudinal guide-rod 12, mounted immediately beneath the ironing-board 1 and 75 secured thereto by means of brackets 13, which take over the ends thereof. The free ends of the hinge-bars are bent at right angles and pass through openings in the legs 8 and are screw-threaded to receive the thumb-nuts 80 18^a. These bent ends form pivots for the hinge-bars.

14 designates grooves formed on the inner sides of the brace-legs 8 and adapted to receive the side arms of the U-shaped hinge-bars 9 and 9^a when clamped in position by means of the clamps 15, slidably secured to the brace-legs 8 by means of the staples 16, secured to the outer sides of said brace-legs 8. 85

17 designates a second set of staples secured 90 to the outer sides of said brace-legs 8 and designed to receive the hooked ends 18 of the clamps 15 when the same are not in use, as shown in Fig. 5 of the drawings.

It will be seen upon referring to Fig. 7 that 95 the hooked ends of the clamps 15 are provided with a wedge or pointed end, as at a, to more readily engage and clamp down the side arms of the U-shaped hinge-bars 9 and 9^a.

18^a designates thumb-nuts secured to the 100 outer bent ends of the side arms of the hinge-bars 9 and 9^a, which pass through the brace-legs 8.

19 designates pins secured to the side bars 2 of the step-ladder and designed to take 105 through the slotted arms 6 of auxiliary board 5 and into one of the openings 20, arranged along said side bars 2, and hold said board 5

in any desired position to support a scrub-bucket or other article when the device is used as a step-ladder.

21 designates a thumb-screw mounted in the sliding sleeve 11, and by moving the sleeve 11 to the right or left on the guide-rod 12 the ironing-board 1 is raised or lowered to any desired height and locked in that position by tightening the thumb-screw to the guide-rod 12. In the same way the inclination of the step-ladder may be varied.

When desiring to change the parts from their position shown in Fig. 2 as an ironing-board to that shown in Fig. 1 as a step-ladder, 15 the device is turned up on end with the pointed end of the ironing-board resting on the floor. The auxiliary board 5 is brought to assume the position shown in Fig. 1. The clamps 15 are loosened and turned outwardly, 20 as shown in Fig. 5. The thumb-nuts 18^a are loosened so that the side arms of the U-shaped hinge-bars 9 and 9^a may be thrust out of the grooves 14 of the brace-legs 8. The little thumb-screw 21 under the ironing-board 1 is 25 loosened, and the brace-legs 8 are turned over and upwardly, turning the two U-shaped hinge-bars 9 and 9^a and bringing the two brace-legs 8 to assume a position alongside of the pointed end of the ironing-board, with 30 the ends of the brace-legs 8 (formerly the upper ends) now resting on the floor. In this position the hinge-bar 9^a can enter the groove 14 of the legs, and the hinge-bar 9 serves as a brace, extending from the legs to the step-ladder. 35

The clamps 15 are now clamped about the side arms of the U-shaped hinge-bar 9^a. The thumb-nuts 18^a and the thumb-screw 21 are tightened and a perfect step-ladder is formed. 40 The purpose of the brace-legs 8 when the device is in this position is merely to properly brace the step-ladder as against any swinging or lateral motion.

By loosening the clamps and thumb-nuts 45 and set-screw the parts may be returned to their former position to form an ironing-board and then folded, as shown in Fig. 5 of the drawings, or the parts may be folded at once in this position.

50 In Fig. 3 is shown a modification of the sliding hinge-bar fastening 10, in which the bearing for the hinge-bar 9^a is formed by a laterally-extending wire 22, having its ends bent to form loops 23, engaging the hinge-bar, instead of having the metal bent around to form a tube-bearing 24, as shown most clearly in Fig. 6 of the drawings.

It is evident from the foregoing that I provide a combined ironing-board and step-ladder 60 which is the embodiment of simplicity and durability of construction, which can be manufactured at a very small price, which can be quickly adjusted for use, and which when not

in use occupies a very small amount of space and which is efficient and practical in every respect. 65

Various changes in the form, proportion, and the minor details of construction may be resorted to without departing from the principles or sacrificing any of the advantages of 70 this invention.

Having thus described my invention, what I claim, and desire to secure by Letters Patent, is—

1. A combined ironing-board and step-ladder, consisting of an ironing-board, a step-ladder hingedly attached to one end thereof, an auxiliary board pivotally attached thereto, brace-legs pivotally secured to said ironing-board and step-ladder, by means of a pair of 80 substantially U-shaped hinge-bars connecting said brace-legs, and means for securing said U-shaped hinge-bars to said brace-legs. 75

2. A combined ironing-board and step-ladder, consisting of an ironing-board, a step-ladder hingedly attached thereto, brace-legs pivotally secured to said ironing-board and step-ladder, by means of a pair of U-shaped hinge-bars connecting said brace-legs one of 85 which is pivotally secured to the step-ladder and the other of which is pivotally secured beneath the ironing-board, a longitudinal guide-rod mounted beneath the ironing-board, a hinge-bar fastening provided with a sleeve 90 slidably mounted upon said longitudinal guide-rod and hingedly connected to said last-mentioned U-shaped hinge-bar, and means for securing said U-shaped hinge-bars to said brace-legs. 95

3. In a combined ironing-board and step-ladder, the combination with an ironing-board, and a step-ladder hingedly secured to one end thereof; of brace-legs pivotally secured to said ironing-board and step-ladder by means of U-shaped hinge-bars, said U-shaped hinge-bars connecting said brace-legs, and means for securing said U-shaped hinge-bars to said ironing-board and step-ladder. 100

4. A combined ironing-board and step-ladder, consisting of an ironing-board and step-ladder hingedly attached together, a pair of brace-legs, a pair of U-shaped hinge-bars connecting said brace-legs one of which is pivotally secured to the step-ladder and the other of which is pivotally secured beneath the 110 ironing-board, means for securing and adjusting one of said hinge-bars to the ironing-board, and means for securing said hinge-bars to said brace-legs. 115

In testimony whereof I have affixed my signature in presence of two witnesses. 120
